GEORGE B. THOMAS
By his Attorneys,

None and None

UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

LUMINOUS PENDANT.

1,230,626.

Specification of Letters Patent. Patented June 19, 1917.

Application filed March 28, 1917. Serial No. 157,999.

To all whom it may concern:

Be it known that I, GEORGE B. THOMAS, a citizen of the United States of America, and residing at Bridgeport, in the county of 5 Fairfield and State of Connecticut, have invented a certain new and useful Improvement in Luminous Pendants, of which the following is a specification.

My invention relates to luminous pendants and particularly to a pendant of the type adapted to indicate the location of the pull member for operating an electric switch, and the object of my invention is to provide a durable mounting for luminous 15 material and of such nature that it may be readily attached to the pull member.

In the accompanying drawings,

Figure 1 is a vertical section through a pendant in which my invention is embodied 20 in one form;

Fig. 2 is an inverted plan thereof;

Fig. 3 is a broken elevation of a modified construction of the pendant;

Fig. 4 is an inverted plan thereof; and

Fig. 5 is a plan of a retaining washer.

In the construction shown in Fig. 1 the pendant comprises a transparent housing 10 having a central bore 11 within which fits a tube 12 of luminous material. A rivet 13 passes through the tube 12 and supports the latter on a shoulder 14 at its lower end, while the rivet head 15 lies below the casing 10. Overlying the upper end of the latter is a washer 16 having a boss 17 which enters the central bore of the casing 10 and through which passes the rivet 13, the head 18 of which overlies the washer and retains the parts in assembled position. The margin of the washer extends beyond the area of 35 the casing 10 and affords a shoulder over which the lower edge of the cap 19 may be crimped. The coupling sleeve 20 has at its lower end a shoulder 21 supporting the cap 19, while its upper end is apertured 40 at 22 to admit the end ball of the pull chain 23, the link 24 of the chain passing through a slot 25 which communicates with the aperture 22 and permits the chain to rise into axial position with relation to the 45 pendant.

In the construction which as shown in Figs. 3, 4 and 5 the transparent casing 26, which in both cases is preferably of glass, has a cen-

tral well 27 which is substantially filled with luminous material 28. A plug 29 of any 55 suitable character to prevent deterioration of the luminous material is preferably placed above the latter and is held in position by the washer 30 which overlies the upper face of the casing. Notches 31 cut in the margins 60 of the washer 30 receive the arms of a spider 32 which supports the casing, the upper ends of the arms being crimped over the upper face of the washer 30. The cap 19 and coupling sleeve 20 are of the same construction 65 as above described for connecting the pendant to the terminal ball of a pull chain.

In both constructions the luminous material is completely incased and protected against deterioration, while the constructions are both economical to manufacture 70 and readily attached to the pull chain for use with which they are designed.

I do not limit my invention to the precise forms of construction illustrated, which may 75 be variously modified without departing from what I claim as my invention.

I claim:

1. A luminous pendant of the type described, comprising a chambered translucent 80 casing, luminous material within the chamber of said casing, a washer overlying said chamber, a cap secured to said washer and a coupling sleeve connected to the cap and affording means for detachably connecting 85 the pendant to a chain.

2. In a luminous pendant, a translucent casing having a central bore, luminous material of tubular form fitting within said bore, and a securing member passing 90 through said tubular luminous material and serving to hold the latter in the casing.

3. A luminous pendant, comprising a translucent casing having a central bore, a tube of luminous material fitting within said 95 bore, a rivet passing through said bore and securing the luminous material in the latter, together with means for detachably connecting said pendant to a chain of the type described.

In testimony whereof I have signed my name to this specification.

GEORGE B. THOMAS.
